ELECTRONIC ORGAN WITH PUNCH CARD REGISTRATION SELECTION SYSTEM

Richard H. Campbell, Jr., and George H. Hadden, Laconia, N.H., assignors, by mesne assignments, to The Seeburg Corporation, Chicago, Ill., a corporation of Delaware

Filed Feb. 26, 1960, Ser. No. 11,343

5 Claims. (Cl. 84—1.03)

This invention relates to electronic musical instruments and more particularly to electronic organs.

The object of this invention is to provide an electronic organ having means controlled by a punch card for automatically closing selected stop switches to provide a predetermined organ registration.

Another object of this invention is to provide an electronic organ having punch card controlled means for automatically closing a selected combination of stop switches to establish a desired organ registration, each switch having a visible key which is accessible to the player so as to permit manual modification of the organ registration set up by operation of said punch card controlled means.

A further object is to provide punch card controlled means for canceling an existing organ registration and automatically setting up a new predetermined registration.

Other objects and many of the attendant advantages of the invention will be readily appreciated as the invention becomes better understood by reference to the following detailed description when considered in connection with the accompanying drawings, wherein:

FIG. 1 is a block diagram of an organ embodying the present invention;

FIG. 2 is a perspective view of the upper half of an electronic organ embodying the present invention;

FIG. 3 is a side view of one of the stop key units consisting of a stop switch and a stop key or tablet;

FIG. 3a is a plan view of a typical stop key;

FIG. 4 is a perspective view of a push button combination switch assembly which is adapted to accept five punched cards, each of which permits attainment of a different combination of stop settings;

FIG. 5 is an enlarged sectional view taken along line 5—5 of FIG. 4;

FIG. 6 is an enlarged sectional view taken along line 6—6 of FIG. 5;

FIG. 7 is a plan view of a blank punch card;

FIG. 7a is a perspective view of the same card with a plurality of holes punched therein in a predetermined pattern; and

FIG. 8 is a schematic diagram of the circuitry embodied in the Punch Card Registration Selection System.

The present invention is embodied in an electronic organ whose organization is shown generally in FIG. 1. The outputs or tone signals (C, C#, D, D#, etc.) of a plurality of tone generators 51 are selectively coupled to an output system 53 by switches which are operated by keys in two keyboards 55, 57, properly identified as the swell and great manuals. Although not shown, it is to be understood that additional tone signal selection may be afforded by pedal switches operated by depressing selected foot pedals. The selected tone signals are amplified by suitable bus amplifiers 59, 61 and then applied to the output system 53. The output system 53 is outlined by a broken line in FIG. 1. It includes a plurality of stop switches 63 which normally are operated manually by manipulation of stop keys 8 located on the front of the organ. The stop switch organization 63 is commonly called a "stop action assembly." These stop switches 63 operate to channel

2

tone signals selected by playing of both keyboards 55 and 57 to a plurality of voicing circuits 65, 67, each voicing circuit having its own stop switch. Certain of these stop switches 63 are depressed by the organist so as to selectively feed the outputs of the voicing circuits 65, 67 first to a vibrato circuit 69 and then to an output amplifier 71, or directly to the output power amplifier 71 if no vibrato effect is desired.

It is to be noted that the tone signals produced by playing of both manuals 55 and 57 may be fed to a common panel or group of voicing circuits, or, as shown in FIG. 1, each manual may have its own panel of voicing circuits 65 and 67, respectively. As used herein, the term "voicing circuit" denotes any circuit which alters the sound or harmonic content of the audio tones normally associated with a given key on the keyboard. These voicing circuits are essentially tone filters which filter the raw tone signals produced by the tone generators and convert them to one of the recognizable organ voices, e.g., flute, obce, diapason, etc.

It is to be noted also that the organ may include other conventional coupling circuits (not shown), e.g., a great to swell 16-foot coupling circuit, or a percussion circuit which will also be cut into or out of operation by means of separate stop switches.

To the extent already described, the organization illustrated in FIG. 1 is conventional and substantially the same as the system shown in FIGS. 1 and 2 of our co-pending application Serial No. 808,098 for "Electronic Organ," filed April 22, 1959, now Patent No. 3,006,229. To this organization there is added a punch card registration selection system. This system operates to turn stop switches ON in a registration, i.e., selection pattern or combination, determined by holes punched in a card inserted into the system through a suitable slot in the front of the instrument. This system also provides means for automatically canceling a previous registration when a new predetermined registration is demanded by the player.

FIG. 2 illustrates the keyboard section of an organ embodying the present invention. The swell keyboard 2 and great keyboard are shown. Above the two keyboards on a flat vertical panel 6 there are several different groups of controls, including a plurality of stop keys 8. Each tablet is connected to one end of the operating lever of a stop switch which is adapted to channel keyed tone signals to a particular voicing circuit. Each tablet or stop key and its associated stop switch makes up a single stop key unit, and the combined group of stop key units is commonly referred to as the "stop action assembly." Preferably, each stop switch is of the type shown in FIG. 3. Details of the stop switches are described hereinafter.

Substantially all of the punch card registration selection system is mounted on the underside of a horizontal metal panel 14 which is located below the stop switch assembly and above the swell manual. Only a portion of panel 14 extends out beyond vertical panel 6; the remainder is located behind it. Formed integral with panel 14 is a vertical panel 16 which has five thin elongated horizontal slots 18, each adapted to receive a punch card. Mounted in panel 16 above slots 18 are five buttons 20. Each of these buttons can activate the punch card registration selection system. A sixth "cancel" button 22 is provided to cancel all stops, whether set previously by the selection system or manually.

FIG. 3 is a side elevation of one of the stop switch units, and it also illustrates how this stop switch unit is connected into the system of FIG. 1. As shown in FIG. 3, each stop switch has a front plate 26 which is attached by suitable screws (not shown) to the rear of

panel 6. Front plate 26 carries two electromagnets 28 and 30, a U-shaped bracket 32, and a lever 34. Lever 34 extends through a suitable slot in plate 26 and is pivotally secured to the plate by a pivot pin 36. To the front end of lever 34 is attached one of the stop keys or tablets 8. The rear end of lever 34 is fitted with an arcuate crosshead 38. It is to be noted that the combination of crosshead 38 and each magnet is essentially a solenoid. The ends of the cores of magnets 28 and 30 are beveled as shown at 40 and 42, respectively, to substantially match the slope of the adjacent surfaces of crosshead. When magnet 28 is energized, it attracts the crosshead, causing the lever to pivot to the OFF position. The OFF position may be considered the normal position, and it is the position occupied by arm 34 in FIG. 3. When magnet 30 is energized, arm 34 is pivoted to the ON position shown by broken lines in FIG. 3.

The rear surface of crosshead 38 is notched, and in the notch is disposed one end of an arm or detent 44 which extends through a hole in the rear leg 43 of bracket 32. This one end of detent 44 is enlarged so as to provide a shoulder 46 which acts as a stop or retainer for a compression spring 48. Crosshead 38 urges detent 44 in a direction to compress spring 48 against the rear leg 43 of bracket 32, and it also functions to pivot the detent from the full line OFF position to the dotted line ON position shown in FIG. 3. The spring acts to keep the detent in the position to which it is moved by operation of lever 34.

Secured to the rear leg of bracket 32 are two terminals 50 and 52 which are insulated from each other and also from bracket 32. Terminal 52 is connected to ground, and terminal 50 is connected to one of the bus amplifiers. Secured to terminals 50 and 52 are respective separate wire contact elements 54 and 56. A third terminal 58 is also secured to bracket 32. Terminal 58 is insulated from the bracket and is normally connected to one of the voicing circuits. Secured to this third terminal is a spring wire contact 60 which tends to engage a horizontally extending portion of contact 54. However, normally it is forced by detent 44 into contact with a horizontally extending portion of grounded contact 56, and it engages contact 54 only when detent 44 is pivoted to its dotted line position. In the latter position, detent 44 exerts no pressure on wire contact 60. The OFF magnet 40 and the ON magnet 42 are energized from a 12-volt source, but energization of the magnets is controlled and effected through the punch card registration selection system. One connection to magnets 28 and 30 is made at respective soldering terminals 62 and 64. The other connection for both magnets is made through a common soldering terminal 66.

FIGS. 4-6 show details of the operating mechanism of the punch card registration selection system which is mounted behind panel 16 on the underside of horizontal panel 14. This mechanism is a combination switch unit, and it essentially contains five push button operated multicontact switches and a sixth push button operated switch having a single pair of contacts. Each of the five push button switches contains one movable contact for each stop key unit, and these movable contacts are disabled by insertion of a punch card, except where holes are punched. Each of these five push button switches also contains a separate movable contact referred to herein as the "start contact," timed differently from the other movable contacts.

The mechanism shown in FIGS. 4-6 comprises a flat rectangular printed circuit board 70 on which thirty-six spaced conductors 72 are mounted. The first and all odd-numbered conductors, identified as 72a in FIG. 6, have enlarged terminal segments 74 at the left-hand end of the board. The second and all even-numbered conductors, identified as 72b in FIG. 6, have enlarged terminal segments 76 at the right-hand end of the board.

Of course, not all of these conductors need be used. The number used depends upon the number of stop key units in the stop action assembly. As pointed out hereinafter, conductors 72 are connected at terminals 74 and 76 to the circuits for energizing the ON magnets.

The conductors 72 are separated into groups so as to leave free spaces to accommodate six rows of screws 78 which cooperate with nuts 80 to clamp angle bars 82 to the underside of the board. Each row of screws (except the leftmost one in FIG. 4) and their associated nuts function to hold down on the upperside of the board a plurality of elongated flat elements consisting of a card guide and spacer 84 formed of insulating material, a metal spacer 86, a flat leaf spring member 88, and a top metal spacer 90. The screws in the leftmost row (FIG. 4) and their associated nuts hold down only a card guide and spacer 84 and a metal spacer 86. Each of the leaf spring elements 88 has a flat, relatively stiff, metal switch plate 94 attached to it adjacent its free longitudinal edge. Attached to the underside of each metal plate 94 is a resilient metal strip 96 formed with a first series of depending, spaced, concave, resilient switch contact members 98 along one edge and a second series of identical switch contact members 100 along the opposite edge. Contact members 98 are disposed alternately with contacts 100, with contacts 98 disposed above conductive strips 72a and contacts 100 disposed above conductive strips 72b. Each spring member 88 is formed so as to maintain contacts 98 and 100 normally out of engagement with the conductive strips 72. FIGS. 5 and 6 illustrate this normal position of contacts 98 and 100. These contacts are raised high enough to permit insertion of a punched card 102 (shown in FIG. 5, but not shown in FIG. 6) which is guided between adjacent spacer plates 84. Contacts 98 and 100 are made to engage conductors 72 by means of switch operating rods 104. It is to be noted that five operating rods 104 are shown in FIG. 4. However, for purposes of illustration, the switch plate 94 normally associated with the leftmost operating rod has been omitted from FIG. 4.

Rods 104 carry buttons 20 referred to previously in connection with FIG. 1. These rods are mounted in two parallel angle supports 106 and 108 and are held in a normal extended position by means of compression springs 110. These springs act between the rear angle iron 108 and collars 112 mounted on the individual rods. Each rod carries a transversely extending pin 114 which rotatably supports two wheels 116. These wheels are normally engaged by switch plate 94; but so long as rods 104 are in extended position, contacts 98 and 100 will remain spaced from the conductive strips 72. However, each plate 94 has a raised arcuate cam follower portion 118. When rods 104 are in extended position, wheels 116 are in front of cam follower portions 118. When rods 104 are depressed (see the second rod from the left in FIG. 4), wheels 116 will engage cam followers 118 and will act on them to cam plates 94 downward so as to cause contacts 98 and 100 to engage conductors 72. Since the switch plates 94 are grounded, engagement of a contact 98 or 100 with a conductor 72 acts to ground that conductor and thereby initiate a sequence of relay switching operations to complete the energizing circuit for one of the ON magnets. Grounding of plates 94 may be effected in several ways. In practice, grounding is effected through panel 14 to which the circuit board is secured by screw connectors 120.

It is to be noted that insulating plates 84 are spaced from each other so as to form a guideway 122 having a width just sufficient to readily receive a punch card 102. FIG. 7 illustrates a card 102 in its unpunched form. The card is made of insulating material, e.g., plastic. As seen in FIG. 7, the card has thirty-six numbered circles 125 arranged in two rows, with the even numbers in one row and the odd numbers in the other row. These thirty-

six circles correspond to the thirty-six conductors 72 on circuit board 70. These circles are so arranged that when the card is inserted fully into a guideway 122 through one of the slots 18, the centers of the even-numbered conductors will be above the even-numbered conductors and the centers of the odd-numbered conductors will be above the odd-numbered conductors. It is to be noted that the rear support 108 for push button bars 104 acts as a stop for the card so as to properly locate the circles above the conductors. If a punched card is located in one of the guideways, it will permit only those contacts which are located above holes 127 therein to make contact with conductors 72, thereby to complete the energizing circuits for the ON magnets of those stop switches whose numbers correspond to the numbers of the circles punched out of the card. At this point, it is to be noted that each stop switch tablet 8 will bear a suitable designation of function, e.g., 8-foot flute, 16-foot cello, etc., plus a number corresponding to a numbered circle on the punched card.

FIG. 3a, for example, shows a tablet 8a for a 4-foot flute stop switch. This tablet has a circle numbered 27. Hence, to have a card function to operate the 4-foot flute stop switch, it will be necessary to punch out the circle having the number 27. FIG. 7a illustrates a card 192 with holes 127 punched in a predetermined pattern. For clarity, the numbered circles have been omitted from this figure. However, it is to be understood that the punched holes are approximately the same size as or slightly smaller than the numbered circles.

The combination switch assembly illustrated in FIG. 4 will accommodate five cards, one in each of the multi-contact push button operated switches. Although operation of any of the push button rods 104 is designed to close selected stop switches, the desired registration will not be attained if a previous registration is not canceled first. Although this cancellation may be accomplished in the regular manner by manually flipping up all tablets 8 that are in down position, it is preferred that cancellation of a previous registration be effected automatically upon pressing in any one of the select buttons 20 or the cancel button 22. For this purpose, the circuit board 70 is provided with two conductors 124 and 126. These two conductors have enlarged terminal segments 128 and 130 at one end for connection to the energizing circuits of all of the OFF magnets of the stop switches. At their opposite ends they are connected by two insulated leads 132 and 134 to switch contacts 136 and 138 respectively which are mounted on a bracket 140 attached to angle bar 106. Contacts 136 and 138 are normally "open," i.e., separated, and they are closed by operation of a push button rod 142 which carries cancel push button 22. A compression spring 144 normally keeps rod 142 extended out of engagement with contact 138. When cancel button 22 is pressed, rod 142 will force contact 138 to close on contact 136, whereupon to cause energization of all of the OFF magnets.

Conductors 124 and 126 may be connected also by operation of push buttons 20. To accomplish this, five pairs of resilient start switch contacts 146 and 148 are secured to conductors 124 and 126. These start switch contacts are located directly in line with the rear ends of rods 104, and they are normally open. They are closed by rods 104 when the rods are depressed. Rods 104 are insulated from contacts 146 and 148 by rubber caps 150 on their rear ends. Contacts 146 and 148 are so located that contact 148 will close on contact 146 after contacts 98 and 100 engage conductors 72, and will reopen before conductors 72 and contacts 98 and 100 are disengaged. The reason for this sequence of operations is set forth below in connection with the description of the circuit in FIG. 8.

FIG. 8 illustrates the circuitry embodied in the punch card registration selection system. The illustrated circuit consists of four parts: (a) a relay system, (b) a D.C. power supply, (c) a limited number of stop key units, and (d) the push button switch circuit limited for con-

venience to the conductors 72a, 72b, and contacts 98 and 100 which are associated with the limited number of stop key units selected for illustration purposes. For convenience of illustration, only five stop key units are shown. 5 These are the first, second, third, thirty-fifth, and thirty-sixth units. The OFF and ON magnet coils 28 and 30 respectively are shown in their correct relative positions, with the ON coils 30 acting to pivot tablets 8 down and the OFF coils 28 acting to pivot them up again.

10 The relay system consists of two relays 160 and 162, each with its own RC time delay circuit and transient suppressing diode. Relay 160 has its coil 164 connected at one end to ground. The other end of coil 164 is connected through a series resistor 166 and a lead 168 to the first side of all of the OFF magnet coils 28. A capacitor 170 is connected across coil 164 in series with resistor 166. Relay 160 has a movable contact 172 which is normally closed on a first fixed contact 174. Relay 160 has a second fixed contact 176 on which contact 172 closes when coil 164 is energized. Fixed contact 174 is grounded. Fixed contact 176 is connected to lead 168. Movable contact 172 is connected to a lead 178 which is common to the second side of all of the OFF magnets 28 and the first side of all the ON magnets 30.

15 Relay 162 has its coil 182 connected at one end to ground. The other end is connected by a series resistor 184 to a first movable contact 186. A capacitor 188 is connected across coil 182. Movable contact 186 is normally closed on a first fixed contact 190 which is connected to common lead 178. When coil 182 is energized, contact 186 closes on a second fixed contact 192 which is connected by a lead 194 to printed circuit conductor 124. The adjacent printed circuit conductor 126 is connected by a lead 196 to the positive side of a 12-volt D.C. power supply 198. The negative side of this power supply is grounded.

20 Relay 162 has a second movable contact 200 which is normally closed on a third fixed contact 202. Contacts 186 and 200 operate together. However, when coil 182 is energized, contact 200 opens relative to fixed contact 202 but does not close on any other contact. Movable contact 200 is connected to lead 194. Fixed contact 202 is connected to lead 168. A first diode 206 is connected between leads 168 and 178 to short out transients produced by current decay in the OFF magnets. A second diode 208 is connected between ground and lead 178 to short out transients produced by current decay in the ON magnets.

25 The second side of each ON magnet coil 28 is connected by a lead 210a-e to a corresponding conductor 72a-e as the case may be. Thus, the #1 conductor 72a is connected by a lead 210a to the ON magnet of the #1 stop key unit, the #2 conductor 72b is connected by a lead 210b to the ON magnet of the #2 stop key unit, the #3 conductor 72c is connected by a lead 210c to the ON magnet of the #3 stop key unit, etc. For convenience, since only five stop units are represented, the leads connecting the thirty-fifth and thirty-sixth conductors 72d and 72e to their corresponding ON coils are designated 210d and 210e, respectively.

30 Operation of the circuit is as follows: When any registration selection button 20 is pressed, conductors 124 and 126 are connected together, and this supplies power through contact 202 of relay 162 to the first side of all of the OFF coils. Since the second side of the OFF coils is normally connected to ground through contacts 172 and 174 of relay 160, all of the OFF coils will be immediately energized. When this occurs, all of the stop keys or tablets 8 are moved to the OFF position, thereby disconnecting the voicing circuits associated with these stop keys from the bus amplifiers.

35 At the same time that the OFF coils are energized, power coming through contact 202 of relay 162 feeds through resistor 166 to the coil of the first relay 160.

Because of the time constant of resistor 166 and capacitor 170, operation of the first relay 160 is delayed a few milliseconds, thus giving the OFF coils time to restore all of the stop tablets to OFF position before first relay 160 is operated. At this same time, the first diode 206 shorts out the transient produced by the current decay in the OFF coils.

Upon operation of the first relay 160, contact 172 closes on fixed contact 176, thereby connecting the common lead 178 of all of the OFF and ON coils thru contact 202 and switch 148 to the positive side of the power supply. Any of the punch card contacts 98 and 100 which have been allowed to engage their corresponding conductors 72a or 72b by virtue of holes in the punch card 102 will provide a connection to ground for the ON coils to which their corresponding conductors are connected. Since the other (common) side of these ON coils has been connected via contacts 176 and 202 to the positive side of the power supply by operation of first relay 160, the associated ON coils will be energized so as to move their associated stop action keys 8 to the ON position. The stop action keys 8 which will be moved to the ON position are the ones which correspond in number to the punched holes on the control punch card which has been inserted via a slot 18 into the multicontact switch which was actuated by pressing its push button 20.

When relay 160 is energized to open contact 174, and close contact 176, power is also supplied through contact 190 and resistor 184 to the coil 182 of the second relay 162. However, operation of the second relay 162 is delayed by the time constant of its associated resistor 184 and capacitor 188, thereby giving the ON coils time to operate. When relay 162 operates, its contact 202 is opened, thereby removing power from coil 164 of relay 160 and all of the ON coils 30. At this time, diode 208 operates to short out the transient induced in the ON coils and relay 160 releases. Closing of contact 192 operates to establish a holding circuit for relay 162 so as to prevent the system from recycling until the selected push button has been released. When a push button 20 is released contact 148 opens thereby releasing relay 162. Both relays 160 and 162 are thus de-energized and the stop keys 8 corresponding to the hole pattern in the card 102 for the switch button 20 which was actuated are in ON position.

If a push button is released before the second relay 162 has had time to operate, power is removed from the stop action coils by the opening of the start contacts 148 which are operated by the selected push button rod. Again, diode 208 will short out any transient.

It is to be noted that if one of the punched card contacts 98 or 100 should open before either the related start contact 148 or contact 202 of relay 162, its corresponding ON coil would not be connected to any suppressor diode; and, therefore, an objectionable transient would result. Therefore, as described previously, the start contacts 146 and 148 are so located that when a push button 20 is released, the start contact 148 which has been closed by depression of that push button will open before any of the punched card contacts associated with that same push button.

An important feature of the invention described above and illustrated in the drawings is that the stop action keys or tablets 8 may be operated independently of the punch card registration selection system. Thus, if a player inserts a card in an appropriate slot 18 and depresses the associated button 20 so as to obtain the registration or combination determined by the arrangement of holes punched in the card, he can alter the selected combination by turning off stop keys which have been turned on by the automatic selection system, or he may add to the combination by turning on stop keys which have not been effected by the punched card selection system.

A further feature of this invention is the provision of a single cancel button 22 for automatically canceling out any existing stop key registration. It is immaterial how the existing stop key registration was produced, whether by manual operation of the stop keys or by automatic operation under the influence of the automatic punched card control system or both; it will still be canceled fully by operation of the cancel button 22. When button 22 is pressed, contacts 136 and 138 close to couple power to the OFF coils 28 through contacts 200, 202, 172, and 174.

The cancellation effected by operation of the single cancel button or any of the five combination selection buttons is almost instantaneous, and the time required to establish the new combination preset in a punched card is equally fast. This is particularly advantageous where a large number of stops have been turned down and the player desires to cancel all of them in the middle of a particular selection and to establish a new registration without any noticeable interruption in playing.

Obviously, many modifications and variations of the present invention are possible in the light of the above teachings. Therefore, it is to be understood that the invention is not limited in its application to the details of construction and arrangement of parts specifically described or illustrated, and that within the scope of the appended claims, it may be practiced otherwise than as specifically described or illustrated.

We claim:

1. An electronic organ comprising a plurality of tone generators, a plurality of voicing circuits, a stop action assembly having a group of stop switches operable when closed to channel the outputs of said tone generators to different ones of said voicing circuits, separate electrical power means for opening and closing each of said stop switches, an array of contacts respectively energizable for closing said stop switches, means for receiving and registering a removable punch card relative to said array, and manually operable punched card scanning means for first operating said electrically powered means for opening all of said stop switches and then selectively applying electrical power to said stop switch closing means according to a pattern of holes in a given punched card registered with said array.

2. In an organ having a plurality of selectively available voices, the combination comprising a plurality of manually operable stop switches for selecting one or more of said voices, electrical means coupled to said switches and individually operable to select or remove the respective voice controlled by said switches, a plurality of push-button switches selectively operable and connected in circuit with said electrical means for controlling said electrical means and said stop switches coupled thereto in timed sequence first to remove all of said voices and then select a predetermined combination of said voices, each of said push-button switches including an array of contacts respectively energizable to operate said electrical means to select a corresponding voice, means for receiving a removable code card registered relative to said array of contacts, and contactors movable by operating said push-button switches to energize only those contacts in said array corresponding to the code on said card.

3. Apparatus according to claim 2 in which said array of contacts is generally coextensive with the area occupied by said code card when received in said push-button switch and said contactors energize contacts in said array through perforations in said code card.

4. In an organ having a plurality of stop switches each manually operable by means of a stop key for selecting or removing a different stop, first and second solenoids for each stop switch, said first solenoid operating said switch to select a stop and said second solenoid operating said switch to remove that stop, a plurality of multicontact selector switches each having a set of separate switch circuits for individually energizing said first solenoids and a common switch circuit for energizing all of said second solenoids, a control circuit operable upon

actuation of any of said selector switches to energize in sequence said common switch circuit and then said separate switch circuits, means for removably receiving a perforated code card in position relative to said separate switch circuits to determine by the perforate code on said card a predetermined combination of said separate switch circuits, and means for completing only the combination of said separate switch circuits from any one selector switch selected by said code to energize the corresponding combination of said first solenoids.

5. An organ comprising a plurality of stop switches each manually operable by means of a stop key for selecting or removing a different stop, first and second solenoids for each stop switch, said first solenoid operating said switch to select a stop and said second solenoid operating said switch to remove that stop, a plurality of multi-contact selector switches each having a set of separate switch circuits for individually energizing said first solenoids and a common switch circuit for energizing all of said second solenoids, a stop selection contact matrix connected between the respective multi-contacts of said selector switches and said first solenoid of each of said 10 said stop switches, means for completing a selected com-

20 bination of circuits in said matrix for selecting a corresponding combination of said stop switches, an electrical time delay, an energizing circuit connecting all of said common switch circuits for energizing simultaneously all of said second solenoids and said electrical time delay, said electrical time delay being operative to operate said first solenoids of said combination of said stop switches, after the delay introduced by said electrical time delay has permitted all of said second solenoids to operate all 15 of said stop switches to remove all of said stops.
